US0D1056825S

(12) **United States Design Patent** (10) **Patent No.:** **US D1,056,825 S**
(45) **Date of Patent:** **** Jan. 7, 2025**

(54) **BATTERY PACK**

(71) Applicant: **Positec Power Tools (Suzhou) Co., Ltd.**, Suzhou (CN)

(72) Inventors: **Andrea Cestonaro**, Vicenza (IT); **Cheng Wang**, Suzhou (CN)

(73) Assignee: **POSITEC POWER TOOLS (SUZHOU) CO., LTD.**, Suzhou (CN)

(**) Term: **15 Years**

(21) Appl. No.: **29/826,663**

(22) Filed: **Feb. 14, 2022**

(30) **Foreign Application Priority Data**

Aug. 12, 2021 (CN) 202130522793.4
Nov. 10, 2021 (CN) 202130736951.6

(57) **CLAIM**

The ornamental design for a battery pack as shown and described.

DESCRIPTION

FIG. 1 is a perspective view of our new design.

FIG. 2 is a front view thereof.

FIG. 3 is a back view thereof.

FIG. 4 is a left-side view thereof.

FIG. 5 is a right-side view thereof.

FIG. 6 is a top view thereof; and,

FIG. 7 is a bottom view thereof.

The broken lines in the drawings illustrate portions of the battery pack that form no part of the claimed design.

1 Claim, 7 Drawing Sheets
